United States Patent Office

Des. 185,739
Patented July 28, 1959

185,739

HEAD OF A GOLF PUTTER

Morris B. Crawford, Los Angeles, Calif.

Application February 24, 1959, Serial No. 54,724

Term of patent 14 years

(Cl. D34—5)

Fig. 1.

Fig. 5.

Fig. 2.

Fig. 6.

Fig. 3.

Fig. 4.

Fig. 1 is a rear elevational view of the head of a golf putter of my invention;

Fig. 2 is a front elevational view of the head shown in Fig. 1;

Fig. 3 is a top plan view of the head shown in Fig. 1;

Fig. 4 is a bottom plan view of the head shown in Fig. 1;

Fig. 5 is an end elevational view taken from the right side of Fig. 1; and

Fig. 6 is an end elevational view taken from the right side of Fig. 2.

The fragmentary indication of shaft as shown in broken lines is included for illustrative purposes only.

I claim:

The ornamental design for a head of a golf putter, substantially as shown and described.
